A. H. DE VOE.
THREAD TENSION SUPPORT.
APPLICATION FILED JUNE 22, 1918.

1,368,246.

Patented Feb. 15, 1921.

UNITED STATES PATENT OFFICE.

ALBERT H. DE VOE, OF WESTFIELD, NEW JERSEY, ASSIGNOR TO THE SINGER MANUFACTURING COMPANY, A CORPORATION OF NEW JERSEY.

THREAD-TENSION SUPPORT.

1,368,246.

Specification of Letters Patent. Patented Feb. 15, 1921.

Original application filed January 27, 1917, Serial No. 144,847. Divided and this application filed June 22, 1918. Serial No. 241,369.

To all whom it may concern:

Be it known that I, ALBERT H. DE VOE, a citizen of the United States, residing at Westfield, in the county of Union and State 5 of New Jersey, have invented certain new and useful Improvements in Thread-Tension Supports, of which the following is a specification, reference being had therein to the accompanying drawings.

10 This invention relates broadly to a means for supporting the thread-tensioning devices of a sewing machine and more particularly to the means for supporting the tensioning devices for a feed-off-the-arm machine, such as that disclosed in my copending 15 application Serial No. 144,847, filed January 27, 1917, and of which this case is a division.

The object of the invention is to provide 20 a support for the thread-tensioning means so located that the tensions are entirely out of the way and do not interfere in any way with the operator's view of the work-arm, the support also acting to brace the bracket-arm of the machine and secure greater rigidity.

In the embodiment shown the machine is carried by a depending angularly disposed support, at the lower end of which is a body 30 portion from which project a bracket-arm and an L-shaped work-arm, which arms carry stitch-forming mechanism, all as disclosed in my copending application above mentioned. A triangular plate is disposed 35 in the angle between the depending support and the bracket-arm and at one side of the bracket-arm and support, said plate carrying a vertical row of tensions on its inner face. This arrangement places the tensions 40 out of the way and allows an unobstructed view of the work-arm during the operation of the machine. The threads are led from the tensions through suitable guides and controlling devices to the stitch-forming 45 mechanism.

In the accompanying drawings, Figure 1 is a side elevation of the machine showing the angular plate secured between the depending support and the bracket-arm and the tensions carried thereby. Fig. 2 is a horizontal section on the line 2—2 of Fig. 1.

Referring to the drawings, 1 is an angularly disposed flattened hollow depending arm the upper end of which is secured to a

suitable support and whose lower end extends toward the operator. At its lower end the arm 1 is enlarged laterally to form a body portion 2, from which extend the upper bracket-arm 3 and lower work-arm 4. A pulley 5 is mounted on a shaft 6 in the body portion, said pulley being connected by a belt to a drive pulley in the upper end of the hollow arm 1. The shaft 6 actuates the stitch-forming devices carried by the arms 3 and 4, all as fully disclosed in my copending application above mentioned. Cast integral with the arm 1 and disposed in the angle between said arm and bracket-arm 3 is a thin plate or web 7. This plate is located at one edge of arm 3 and near the edge of the 70 angular arm 1. A vertically arranged series of tensioning devices 8 is mounted on the inner face of plate 7, and due to the offset position of said plate the tension devices are located almost wholly within the recess 75 formed between arms 1 and 3. It will be noted from Fig. 2 that the bracket-arm 3 is itself off-set with respect to the work-arm 4, and by the above described arrangement of the tensions they do not in any way interfere with the operator's view of the work. 80 In addition the danger of the threads becoming entangled in the working parts is reduced to a minimum. The threads are led from the tensions to the stitch-forming 85 mechanism in any desired manner, in the example shown the upper two threads being led through a guide 9 and then within the body and to the looper, the next four threads being led through a guide 10 to a take-up 90 mechanism and to the needles, and the bottom thread being led through guides 11 on the face-plate 12 of the machine to a suitable covering thread mechanism. It is obvious that the number of tension devices 95 and means for guiding the thread may be varied to suit conditions.

The plate 7 forms a rigid connection between the arms 1 and 3 and thus aids in reducing vibration.

100 It is apparent that the thread tensions may be supported in other ways than in the specific manner shown and I therefore do not wish to be limited other than by the scope of the appended claims.

Having thus set forth the nature of the invention, what I claim herein is:—

1. In a sewing machine, in combination,

- a frame comprising a flattened depending support, a bracket-arm carried thereby and disposed in angular relation therewith, a work-arm carried by said support, stitch-forming mechanism incorporated in said frame, a plate supported within the angle formed by said depending support and bracket-arm and a series of tension devices carried by said plate.
- 10 2. In a sewing machine, in combination, a frame comprising a flattened depending support, a bracket-arm carried thereby and disposed in angular relation therewith, a work-arm carried by said support, stitch-forming mechanism incorporated in said frame, a plate disposed in the angle formed by said support and bracket-arm and substantially flush with one side face of said flattened support, and a series of tension devices carried by said plate and disposed mainly between the planes defined by the opposite side faces of said flattened support.
- 15 3. In a sewing machine, an angularly disposed support, a work-arm extending from said support, a bracket-arm also extending from said support and spaced from and laterally offset with respect to said work-arm, a web extending between said angular support and bracket-arm and offset with respect thereto, and thread-tensioning means mounted on said web, whereby an unobstructed view of the work-arm is obtained.
- 20 4. In a sewing machine, a supporting arm,

a bracket-arm extending angularly therefrom and supported thereby, an offset web 35 extending between said arms in a plane substantially parallel with the planes of the arms, and a series of thread-tensioning members supported by said web substantially within the recess between said arms. 40

5. A sewing machine comprising a work-arm and a laterally offset overhanging bracket-arm disposed in substantially parallel planes and provided with coöperating stitch-forming mechanisms, a support for 45 said bracket-arm and disposed at an angle thereto, thread-tensioning devices disposed substantially wholly in the recess between said support and bracket-arm, and means for supporting said tensioning devices. 50

6. A sewing machine comprising spaced work- and bracket-arms, a supporting arm angularly connected to said bracket-arm, and means for supporting thread-tensioning devices in the recess between said last-named 55 arms acting as a brace between said arms.

7. A sewing machine comprising spaced work- and bracket-arms, the latter being offset, a supporting arm angularly connected to said bracket-arm, and offset means for 60 supporting thread-tensioning devices in the recess between said last-named arms.

In testimony whereof I have signed my name to this specification.

ALBERT H. DE VOE.
